CARBURETOR THROTTLE CONTROL

John Frank Weakley, St. Louis, Mo., assignor to
 Carter Carburetor Corporation, St. Louis, Mo.,
 a corporation of Delaware

Application April 5, 1943, Serial No. 481,846

7 Claims. (Cl. 137—139)

1

This invention relates to valve controlling means for internal combustion engines and more particularly to means for controlling the throttle valve thereof.

In the usual form of carburetor for internal combustion engines there is provided a butterfly type throttle valve having readily accessible means for adjusting the maximum closed position to which the valve can be moved by the throttle return spring for normal idling. Ordinarily, the idling adjustment is effected by means of a screw, carried by the throttle arm, which engages a fixed abutment on the carburetor body to limit the throttle closing movement. However, if the idle adjusting screw should be withdrawn too far, the powerful throttle return spring may wedge the throttle plate within the carburetor barrel resulting in sticking of the valve and damage to the valve plate and barrel. This possibility is of particular importance where the throttle is of the governor type in which the governor spring is relied upon, normally for opening the throttle. In such case, the spring may not be strong enough to dislodge a wedged throttle and the valve may be thereby rendered inoperative.

The main object of the present invention is to provide means for overcoming this disadvantage by preventing wedging of the throttle valve plate and, additionally, providing means for positively opening the valve in case of non-functioning of said first means or the governor spring.

This object and other more detailed objects hereafter appearing are attained by the device illustrated in the accompanying drawing in which

Fig. 1 is a side view of part of a carburetor embodying the invention, portions being sectioned for clearer illustration.

Fig. 2 is a partial side view and section taken substantially on the corresponding section line of Fig. 1.

Fig. 3 is a partial side view and section taken on the line 3—3 of Fig. 1 and

Fig. 4 is an elevation showing the throttle operating lever and idle adjusting means.

The figures show a downdraft carburetor including a barrel 6 and adjacent constant level chamber 7. At the lower end of the barrel there is provided a butterfly throttle plate 8 mounted off center on a shaft 9 journaled in suitable bearings 10 and 11 and projecting therebeyond at both ends.

On the left hand end of the throttle shaft, (Figs. 1 and 3) there is rigidly attached a cam-like lever 14 to which is secured a spring strip 15

2

by means of a screw 16. The spring strip is secured at its other end to a coiled spring 17 which is partially threaded on the extremity of an adjusting screw 18 pivoted at 19. The cam lever and spring are enclosed within a governor housing 20 mounted on the side of the carburetor barrel. Screw 18 extends into an extension 21 of the housing where it is provided with an adjusting slot 22. These parts comprise substantially a known governor in which spring 17 constantly tends to open the unbalanced throttle plate 8 against the force of air flow downwardly through the carburetor barrel.

A projection 25 on cam lever 14 is adapted to engage a stop 26, secured to the inner wall of housing 19 by an eccentric screw 27, just as the throttle plate reaches its fully closed position. The setting of this eccentric is permanently effected in the factory as a part of the assembling operation and, in service, it is unaccessible except upon removal of cover 28. The slot in screw 27 may be closed to further defy tempering.

On the other end of throttle shaft 9 there is provided a lever having opposed arms 29 and 30, the former being pinned at 31 to a link 32 connected to piston 33 slidable in dash pot cylinder 34 which functions to dampen pulsations of the throttle valve. This arm is also provided with a lip 35 for a purpose to be mentioned later.

The above parts are received within a casing 36 which is formed as an integral part of the carburetor barrel, and is provided with a cover plate 37. This cover plate is centrally enlarged at 38 and journals a stub shaft 39 to the inner end of which is rigidly secured an operating member having projecting fingers 40 and 41. At the outer end of shaft 39 there is rigidly secured a throttle operating arm 42 to the upper portion of which there is fastened a link 43 extending to the usual accelerator pedal adjacent the driver's seat. There is also provided the usual throttle return spring diagrammatically indicated at 44. Spring 44 is more powerful than governor spring 17 so that when the accelerator pedal is released by the driver, the throttle will be moved to its closed position.

Control arm 42 is also provided with a threaded boss 45 receiving idle adjusting screw 46 disposed to engage an abutment 47 on cover plate 37. Normally, screw 46 will be adjusted so that the throttle valve will be held slightly open during normal idling, permitting sufficient air to pass the throttle to form a suitable combustible mixture with the idling fuel emerging from port

48. Thus, projection 25 on cam lever 16, normally, will not contact eccentric 26. However, since adjusting screw 48 is readily accessible and is frequently adjusted by unskilled persons as well as mechanics, this screw may be withdrawn too far so as to permit the throttle plate to engage the walls of the carburetor barrel. In such case, the engagement of eccentric 26 by the finger 25 prevents sticking and damaging of the throttle plate.

Finger 40 cooperates with arm 38 to close the throttle, under the influence of return spring 44, when the accelerator pedal is released. Finger 41 on the stub shaft normally has no function, since when return spring 44 is counteracted by depressing of the accelerator pedal, the throttle plate will be moved outward to the extent permitted by the counterforce of the air flow through the carburetor and the positioning of finger 40. However, in case of failure of spring 47 because of sticking of the throttle or for any other reason, and also should eccentric 27 or finger 25 be excessively worn or damaged, so as not to function properly, finger 41 on the throttle control lever will engage lip 35 on arm 28, when the accelerator pedal is fully depressed, to positively open the throttle a slight amount, while the substantially complete governing range of the throttle is not affected. Thus, the carburetor will remain operative to run the engine at a slow speed even though the governor should fail.

The type of carburetor and governor shown are not essential and, in fact, the emergency mechanism may be varied as will occur to those skilled in the art. The exclusive use of all such modifications as come within the scope of the appended claims is contemplated.

I claim:

1. In combination with an internal combustion engine intake conduit, a throttle therein, means to yieldingly open said throttle, a device for closing said throttle against said means, readily accessible means to adjustably limit the closing of said throttle for normal idling, and an additional, less accessible device to prevent closing of said valve far enough to cause wedging or sticking thereof in said conduit.

2. In combination with an internal combustion engine intake conduit, a throttle therein, means to yieldingly open said throttle, manual throttle control mechanism including a spring for normally closing said throttle against said yielding means, a readily accessible adjusting device for limiting the closing of said throttle to a partially open, normal idling position, and an additional device limiting the closing movement of said throttle to prevent wedging and sticking thereof in said conduit.

3. In combination with an internal combustion engine intake conduit, a throttle therein, means to yieldingly open said throttle, manual throttle control mechanism including a spring for normally closing said throttle against said yielding

means, arm structure movable with said throttle, abutment structure adjacent said arm structure, an idle adjusting screw mounted in said structure for adjustably limiting the closing of said throttle to idling position, and an additional device cooperable with said structure to permanently prevent closing of said throttle far enough to cause wedging and sticking thereof in said conduit.

4. In combination with an internal combustion engine intake conduit having a butterfly throttle therein, spring means to open said throttle, more powerful spring means for closing said throttle, manual means to retract said latter spring means to permit opening of said throttle by said first spring means, arm structure movable with said throttle, an abutment adjacent said structure, an idle adjusting screw carried by said structure and cooperable with said abutment to fix the idling position of said throttle, and an additional device cooperable with said arm structure to permanently prevent closing of said throttle far enough to cause wedging thereof in said conduit.

5. In combination with an internal combustion engine intake conduit having a throttle therein and main and idling fuel supply systems, means to nearly close said throttle for normal idling, means to adjust the idling position of said throttle, and means to permanently limit closing movement of said throttle to the fully closed position to prevent sticking and damaging thereof in case of faulty functioning of said closing means.

6. In combination with an internal combustion engine intake conduit, a flow responsive butterfly throttle therein, yielding means to open said throttle, manual control mechanism including a throttle return spring more powerful than said yielding means, arm structure movable with said throttle, an idle adjusting screw carried by said arm structure, and a pair of abutments adjacent said structure, one for engagement by said screw and the other for cooperating with said arm structure to prevent closing of said throttle far enough to cause wedging thereof or damage thereto regardless of the position of said adjusting screw.

7. In combination with an internal combustion engine intake conduit, a butterfly throttle therein and responsive to pressure in said conduit, a spring normally tending to open said throttle, throttle control mechanism including a part for closing said throttle at the will of the operator, a device for adjustably limiting the closing of said throttle to idling position, and a protective device for preventing closing of said throttle far enough to cause sticking thereof, said control mechanism also including a part constituting a one-way operative connection with said throttle for insuring opening of said throttle in case of non-functioning of said opening spring of said protective device.

JOHN FRANK WEAKLEY.
